UNITED STATES PATENT OFFICE.

CURTIS HOLLAND, OF BUTTE, MONTANA.

DESIGN FOR AN ELECTRIC-LIGHT BRACKET.

No. 39,924.

Specification for Design.

Patented April 20, 1909.

Application filed October 24, 1908. Serial No. 459,438. Term of patent 7 years.

To all whom it may concern:

Be it known that I, CURTIS HOLLAND, a citizen of the United States, residing at Butte, in the county of Silverbow and State of Montana, have invented a new, original, and ornamental Design for an Electric-Light Bracket, of which the following is a specification, reference being had to the accompanying drawing, forming part thereof.

This design is illustrated in perspective view, showing an electric light bracket of the following description.

A back support, representing the wheel of a mine ore-car, serves to support an outwardly projecting and upwardly curved arm,

which is attached to the hub of said wheel. An electric socket, of the chain-pull type, is mounted on the end of the upwardly curved arm, and an incandescent electric lamp, of the candle pattern, is held by the said socket, and a miner's candle-stick is supported by the socket, as shown.

I claim:

The ornamental design for an electric light bracket, as shown and described.

CURTIS HOLLAND.
